UNITED STATES PATENT OFFICE.

MATILDA ROOME, OF WASHINGTON, DISTRICT OF COLUMBIA.

DESIGN FOR A CHAIR.

SPECIFICATION forming part of Design No. 18,786, dated December 4, 1888.

Application filed November 7, 1888. Serial No. 290,255. Term of patent 3½ years.

To all whom it may concern:

Be it known that I, MATILDA ROOME, a citizen of the United States, residing at Washington, in the District of Columbia, have invented and produced a new and original Design for a Chair, of which the following is a specification.

The essential features of my new and original design comprise a seat approximately triangular in outline, and a back and rear legs formed by two rods which intersect and cross one another at an apex of the seat.

The drawing illustrates in perspective a chair embodying my design.

Referring to the drawing, A designates the seat of approximately triangular configuration, and B B rods forming the back and rear legs, which intersect and cross one another at the rear apex of the seat, the plane of the latter being about at right angles to that of the rods.

The chair is provided with front legs and also with bracing-rod.

In addition to the above-described essential features of the design, I may include in one 25 of the open spaces formed by the chair a representation in suitable thread of a spider's web.

I claim as new and original—

The design for a chair herein described and 30 shown, the same consisting of a seat approximately triangular in outline, and a back and rear legs composed of two rods that intersect and cross one another at an apex of said seat.

In testimony whereof I affix my signature in 35 the presence of two witnesses.

MATILDA ROOME.
